RACK FOR SERVING FOOD

John F. Bonistall, Zanesville, Ohio, assignor to Shawnee
Pottery Company, Zanesville, Ohio, a corporation of Ohio

Application March 1, 1955, Serial No. 34,813

Term of patent 14 years

(Cl. D44—10)

FIG. 1

FIG. 3

Fig. 1 is a perspective view of a rack for serving food illustrating my novel design;

Fig. 2 is a top plan view thereof; and

Fig. 3 is a side elevation thereof.

What I claim is:

The ornamental design for a rack for serving food, as shown.
